UNITED STATES PATENT OFFICE.

LOUIS E. GILES, OF NEW YORK, N. Y., ASSIGNOR TO UNDERWOOD COMPUTING MACHINE COMPANY, OF NEW YORK, N. Y., A CORPORATION OF NEW YORK.

COMPUTING-MACHINE.

1,370,427.

Specification of Letters Patent.

Patented Mar. 1, 1921.

Application filed October 17, 1919. Serial No. 331,341.

To all whom it may concern:

Be it known that I, Louis E. Giles, a citizen of the United States, residing in New York, in the county of New York and State of New York, have invented certain new and useful Improvements in Computing-Machines, of which the following is a specification.

This invention relates to improvements 10 in computing machines, and is herein disclosed as applied to an Underwood-Hanson combined typewriting and computing machine, one form of which is illustrated and described in the Minton Patent, No. 15 1,280,065, granted September 24, 1918; but the invention is not limited in its application to a machine of that particular type.

A machine of the character disclosed in the aforesaid Minton patent comprises 20 means for rotating the number-wheels of a totalizer in accordance with the digits of a number to be added, if the number represents a positive quantity, and for rotating the number-wheels in the same direction in accordance with the complements of the 25 digits of a number to be added, if the number represents a negative quantity. This is accomplished in accordance with the well-known method of subtraction by complementary addition.

Such a machine will satisfactorily add 30 positive and negative numbers and give correct results, so long as the aggregate of the positive numbers computed is greater than the aggregate of the negative numbers. It will not, however, except by indirect methods, or by indirect readings, give correct results when the aggregate of the negative numbers computed exceeds the aggregate of the positive numbers, that is, when the computation requires the machine to "pass through zero," as that expression is used in the art.

One object of the present invention is to 40 produce an algebraic computing machine, that is, one capable of adding positive and negative numbers, irrespective of their relative magnitudes, and of exhibiting a direct representation of the correct result, whether 50 positive or negative. To this end, each of the number-wheels of the totalizer is provided with two sets of figures arranged in inverse order thereon; the figures of one set to be used to indicate positive totals, and 55 those of the other set to indicate negative

totals, but this modification alone is not sufficient to accomplish the end sought.

As is now well known to those skilled in the art, a machine of the character thus far generally described, if required to add 60 positive and negative numbers, irrespective of magnitude, and give correct results, whether the same be positive or negative, must also be provided with means for adding an additional unit (commonly called the 65 fugitive unit), whenever a number is added which is of greater magnitude than the number previously accumulated in the totalizer, if said numbers are of different character, so as to cause the machine to pass 70 through zero. The additional unit must always be of the same character as the number added.

In the preferred form of my invention as herein disclosed, provision is made for 75 adding the fugitive unit by novel mechanism which may be controlled, in part, by the usual case-shift key of the typewriter, and, in part, by one of the usual typewriter number keys, as, for example, the "1" key. 80 The type-bar, operated by the key selected for this purpose, is not as herein disclosed, provided with a type for printing in upper case.

The invention, in the form herein disclosed, also includes an index, in the nature of a shield or shutter for the totalizer, which may be moved to different positions, and thus caused to selectively point out or direct attention to figures of one or the other 90 of the different sets on the number-wheels, the figures from which a positive result is to be read being indexed by one position of said shutter, and those from which a negative result is to be read being indexed by 95 the other position thereof. Provision is made for operating this shutter by novel mechanism which may also be controlled, in part, by said typewriter case-shift key, and, in part, by said number-key. 100

The invention may also include means for locking all of the number-keys of the typewriter, except the "1" key, when the typewriter carriage is shifted to its upper-case position, so as to prevent the accidental operation of a key other than the one selected to shift the shutter and introduce the fugitive unit.

If desired, one "9" of the number-wheel of the highest denominational order may 110

be replaced by a minus sign, and the other by a plus sign, for a purpose which will be explained.

A machine of the above-described character, with my improvement incorporated therein, may be used in the usual manner to effect ordinary arithmetical addition and subtraction, but, should a negative number be added which is of greater magnitude than a positive number previously accumulated and registered in the totalizer, what is known as an overdraft would occur, that is, the machine would be caused to pass through zero. This would result, in a well-known manner, in a series of carrying operations from the number-wheel, the operation of which produces the overdraft, from order to order, to the number-wheel of highest order in the totalizer, which would be caused to turn from "0" to "9," or if the above-mentioned substitution of characters has been adopted, the highest number-wheel will be caused to expose a minus sign. The appearance of the "9" or of the minus sign signifies to the operative that the machine has passed through zero, and that the result exhibited by the totalizer is not the true result.

Whenever it thus appears that an overdraft has occurred, the operative with the usual subtraction-key of the computing machine set for subtraction, depresses the usual typewriter caseshift key, then depresses the usual "1" key of the typewriter, as if to write "1," and operates the general operator of the computing machine. Such operation of the machine will cause the fugitive unit to be added in the totalizer and the shutter to be shifted, so as to expose the figures from which the correct negative total is to be read, to the exclusion of all others.

The shutter-operating mechanism and the mechanism for inserting the fugitive unit will not call for further attention, so long as the successive results registered in the totalizer remain negative. Should a positive number be subsequently added, which is of greater magnitude than the negative result previously accumulated and registered in the totalizer, a "9," or, if the above-mentioned substitution of characters has been made, a plus sign will appear on the highest number-wheel, and will signify to the operative that the machine has again been caused to pass through zero, and that the number exhibited is not the true result. With the machine set for addition, the operative may then, by simply depressing the shift-key and the "1" key of the typewriter, and actuating the general operator, cause the fugitive unit of the proper character to be inserted, and the shutter to be shifted to expose or point out the correct positive result.

Ordinarily, the shift-key and the "1" key of the typewriter would be depressed to op-

erate the shutter and fugitive unit-inserting mechanism, as above described, only after the carriage has been moved one letter-space beyond the lowest decimal order of a computing zone. The machine may, however, be provided with means for rendering the denomination-selecting indexing mechanism of the computing machine ineffective when the typewriter carriage is moved to uppercase position, so that the shutter and the fugitive unit-inserting mechanism may be operated with the typewriter carriage in any letter-space position without affecting other parts of the computing mechanism.

Other features and advantages will hereinafter appear.

In the accompanying drawings,

Figure 1 is a view, partly in section, and partly in elevation, of a combined typewriting and computing machine of the Underwood-Hanson type, with my invention applied thereto, parts being omitted to avoid confusion.

Fig. 2 is a similar view, showing parts of the mechanism in their operated positions. In this view, the computing mechanism is indicated as being set for subtraction. The typewriter case-shift-key is indicated as being depressed to operate mechanism by which the units rack bar of the totalizer and the shutter-operating rack bar are advanced to pin-setting positions, and to operate mechanism by which the carriage-controlled denomination-selecting mechanism is disabled and by which the typewriter number keys, other than the "1" key, are locked. The "1" key is also indicated as being depressed to operate the pin-setting mechanism to set a pin on the units rack bar and one on the totalizer index or shutter-operating rack bar.

Fig. 3 is a plan view, drawn to a larger scale, showing the rack bars with their indexing devices or pins, the totalizer, its shutter or indexing device, and the shutter-operating mechanism.

Fig. 4 is a view, partly in section, and partly in side elevation, of the shutter-operating mechanism shown in Fig. 3. In this view, the shutter is illustrated in a position such as to permit a positive reading to be taken from the totalizer, and the shutter-operating mechanism, including the rack-bar, interponent, and cross-bar of the general operator, in the positions in which they would appear at the end of the stroke of the general operator which results in the shifting of the shutter to the position shown.

Fig. 5 is a diagram of the developed peripheral surface of one of the number-wheels, illustrating its two sets of oppositely arranged figures.

Fig. 6 is a view similar to that shown in Fig. 5, but illustrating a modification in accordance with which characters and figures

may be applied to the number-wheel of highest denominational order. In this view, the two "9"'s are replaced, one by a plus sign, and the other by a minus sign.

5 Fig. 7 is a detail view in front elevation of mechanism for locking all of the number keys of the typewriter, when writing commas to point off a number, or when writing a decimal point, or for locking all of the 10 number-keys except a key operated to write a zero or a digit until such operation is completed. This view also shows, at or near the left end, the special means for locking all of the number-keys except the "1" key 15 when the case-shift-key is depressed.

Fig. 8 is a view, partly in section, and partly in side elevation, of the parts shown in Fig. 4, drawn to a larger scale. This 20 view illustrates the shutter in such a position as to permit a positive reading to be taken from the totalizer and all other parts in normal position.

Fig. 9 is a similar view of the same parts of the mechanism, illustrating the shutter in 25 such position as to permit a negative reading to be taken from the totalizer, and the shutter-operating mechanism, including the rack-bar, its indexing pin, and the driving element of the general operator, in the positions in which they would appear at the end 30 of the stroke of the general operator, which results in the shifting of the shutter to the position shown.

Fig. 10 is a diagrammatic detail view, in 35 perspective, showing certain of the novel elements of the mechanism detached from the other parts of the machine.

The machine to which my invention is 40 herein disclosed as being applied, in the exemplification selected for illustration, comprises an Underwood typewriter designated generally by the reference character 20, mounted on a computing machine of the Hanson type similarly designated by the reference character 21. Such a machine 45 comprises, among other things, (see Fig. 1) alphabet keys 22 and number keys 23 mounted on key-levers 24 connected, through bell-crank 25, to type-bars 26, so that on depression of any of said keys the corresponding 50 type-bar will be swung upwardly and rearwardly to bring lower-case types 27 to a printing point at the front of a platen 28 mounted in a letter-spacing carriage 29.

55 This carriage is mounted for step-by-step letter-spacing movements in a direction parallel with the axis of the platen under the control of an escapement mechanism, designated generally by the reference character 60 20. This escapement mechanism comprises a rack 31 mounted on the carriage 29, and having engagement with a pinion 32 connected to an escapement wheel 33, which is controlled in its rotation by a pair of dogs 65 34, which, in turn, may be rocked back and

forth by a universal frame 35. This frame is moved at each depression of an alphabet key 22 or number key 23 by a heel 36 on the corresponding type-bar, which engages the frame 35, when the type-bar is swung to 70 bring its type to the printing point. The carriage 29 is constantly urged to move in a direction from right to left (looking at the machine from the front) by a spring-motor (not shown). 75

The machine may also be provided with the usual or any other appropriate tabulating mechanism for effecting rapid movements of the carriage 29 to any desired letter-space position. Such mechanism may 80 comprise keys 37, which, through the intermediary of mechanism (not shown) may cause decimal stops 38 to be projected into the path of movement of column-stops 39, which may be adjustably positioned on a 85 tabulator stop-bar 40. The rack 31 is mounted on arms 41 pivotally secured to the carriage 29, so that on depression of any of the keys 37, said rack may be raised (by means not disclosed), and thus disengaged 90 from the pinion 32, thereby allowing the carriage to be moved by its spring-motor until the column-stop 39 contacts with the set decimal stop 38. Such mechanism is in 95 common use, and is disclosed in many patents of the prior art, for example, see the patent to Minton, heretofore referred to.

The platen may be mounted in the letter-spacing carriage through the intermediary of a shift frame 42, which may be movably mounted in said letter-spacing carriage, so that the platen may be shifted from the position indicated in Fig. 1, in which the lower-case types 27 may be brought to the printing point, to an elevated position, in 100 which upper-case types 43 may be brought to the printing point. In the form herein shown, the type-bars operated by the number keys are provided with lower-case types 27, but with no upper-case types 43. To elevate the shift frame, there may be provided the usual case-shift mechanism comprising a key 44 mounted on a lever 45 having an arm 46, which, on depression of said key, will rock a frame 47, which supports a rod 48, 105 forming a rail or runway for a roller 49, mounted on the lower portion of the shift frame 42, and thus cause said shift frame to be raised to upper-case position.

The number keys 23 not only operate the 110 number-printing type-bars and control the typewriter escapement, as above described, but also operate means for setting indexing devices so as to set up or index a preliminary representation of the number typewritten in 115 a part of the computing mechanism, which will next be described. For this purpose, each of the number keys representing the digits from "1" to "9" is provided with a depending bar 60 (Figs. 1 and 7), which, 120 125 130

on depression of said key, may engage an arm 61, on a rock-shaft 62, normally connected to an index-setting device or pin-setting linkage 63 (Fig. 1). There is one of 5 these pin-setting linkages normally representative of each of the digits "1" to "9," respectively, and each is normally engaged by an arm 64 extending from the corresponding rock shaft 62. The lower bars or 10 members 65 of the linkages 63 are designed to set indexing devices, herein disclosed as pins 66 (Figs. 1 and 3), mounted in rack-bars 67, having teeth 68 to mesh with the teeth of pinions 69, each connected with a 15 totalizer number wheel 70. The pin-setting mechanism herein generally disclosed is more fully illustrated and described in patents of the prior art, see, for example, Patent No. 1,278,812, granted September 10, 20 1918, to Hans Hanson.

The pins 66 are normally out of effective range of movement of the pin-setting bars 65, but are brought into setting relation with said bars, one by one, in a manner 25 which will now be described. In the aforesaid patent to Hanson, the rack-bars are normally at a level which places the heads of the pins too far below the pin-setting bars to be affected thereby when said bars are operated by the keys, and the setting relation is established by lifting the rack-bars, one by one, by mechanism controlled in accordance with the letter-spacing movement of the typewriter carriage. In this case, however, as in the aforesaid Minton patent, the 30 indexing pins are normally placed out of alinement with the pin-setting bars, (see Fig. 1), so that an operated pin-setting bar would be lowered between two pins and not affect the same. The pins are brought into 35 setting relation (indicated in Fig. 2) by a slight forward movement, one after another, of the rack-bars 67, by means which will now be very generally set forth, the same being more specifically disclosed in the patents 40 of the prior art, see, for example, Patent No. 1,287,301, granted December 10, 1918, to Frederick A. Hart.

To establish the above-mentioned setting 50 relation between the pin-setting bars 65 and the indexing pins 66, denomination-selecting mechanism is provided, which comprises one or more tappets 80, (Figs. 1 and 10), each mounted on a supporting arm or block 55 81, which may be adjustably attached to a rod 82 secured to the typewriter carriage. The tappets 80, during the letter-spacing movement of the typewriter carriage, may be brought *seriatim* into engagement with a 60 series of jacks 83, (Fig. 1), pivoted at 84 in a supporting member 85 secured by brackets 86 to the machine frame. The jacks 83, as they are engaged one after another by a tappet 80, are rocked slightly in a clockwise direction, so as to depress thrust rods 87, one

for each jack, and thereby rock levers 88, one for each rod, which, through transposition linkages 89, may rock bell-crank 90, each having an arm which engages a pin 91 on one of the rack-bars 67, and by which 70 said bars may be slightly advanced one after another to bring the pins 66 in alinement or setting relation with the pin-setting bars 65, as illustrated in Fig. 2.

Inasmuch as the letter-spacing carriage 75 29 travels from right to left, whereas numbers should be indexed in the computing mechanism from left to right, the order in which the rack-bars are advanced to bring the pins into setting relation must be inverse to that in which the jacks 83 are rocked by a tappet 80. This is accomplished by a transposition mechanism including the levers 88, linkages 89 and bell-crank 90 (Figs. 1 and 3), more specifically illustrated and described in the aforesaid Hart Patent No. 1,287,301.

After the digits of a number to be computed have been indexed by setting the pins on the rack-bars 67, the rack-bars are moved 90 forward by means, hereinafter described, so as to rotate the pinions 69 (Fig. 1) and their connected number wheels 70, and thus register the typewritten number in the totalizer, designated generally by reference character 95 100. The number wheels 70 have characters or figures on their peripheries from which the number accumulated in the totalizer may be read at a sight-opening 101 in the machine casing 102. The forward movement 100 of the rack-bars, previously referred to, is effected by a general operator, comprising cross-bars 103, 104 (Fig. 1), secured at their ends to slide bars 105 having teeth 106 in engagement with teeth of pinions 107, which 105 are, in turn, in engagement with teeth of sectors 108 fast upon a shaft 109, which may be rotated by an upwardly and rearwardly extending crank handle (not shown), commonly used on machines of this character. 110 On pulling said handle forward, the rotation of pinions 107 by sectors 108 will cause the slides 105 to be moved forward and thereby advance the cross-bars 103 and 104. The cross-bar 103 lies just below the rack-bars 67, and the ends of the pins 66, when 115 set, are projected downwardly into the path of movement of said cross-bar, so that, on forward movement of said bar, the rack-bars in which pins have been set will also be moved forward. The distance each rack-bar will be advanced, and the amount that its corresponding number wheel will be rotated, will be determined in each instance by the particular one of the indexing pins on 120 said rack-bar which has been set.

The totalizer is provided with tens-carrying mechanism, which may be of the type commonly used in machines of the character herein described, for causing each number 125 130

wheel, except that of units order, to be advanced one step whenever the wheel of next lower denominational order is moved from its "9" position to its "0" position. Such carrying mechanism may include the usual transfer members 120; (Fig. 1), carry-over assisting members 121, and holding pawls 122 and 123. The connections between the pinions 69 and the number wheels 70 are 10 in the nature of one-way clutches (illustrated and described in detail in the afore-said Hanson patent), such that said number wheels are rotated in a clockwise direction on forward movement of the rack-bars, but 15 on rearward movement of said bars, the pinions 69 may rotate idly while the number wheels 70 are held by the pawls 122, unless advanced by the carrying mechanism. The carry-over assisting devices 121 are rotated 20 during the return of the slide bars 105 of the general operator as the result of the engagement of teeth 124 with the teeth of a pinion 125, which, in turn, engage the teeth of a pinion 126, having a one-way driving connection (also illustrated and described 25 in said Hanson patent) with the shaft 127 on which said carry-over assisting devices are mounted. On forward movement of the slide bar 105, the one-way connection between the pinion 126 and shaft 127 permits 30 the pinions 125 and 126 to rotate idly without rotating said shaft. Carrying mechanism of the type herein very generally disclosed is in common use, and is fully illustrated and described in the patents of the prior art, for example, see the aforesaid Hanson patent.

On return of the general operator, cross-bar 103 engages lugs 128 (Fig. 1) on the 40 rack-bars 67, which are thereby returned to their normal positions. On return of the general operator, the set indexing pins are also restored to normal positions. This is effected by a pin-resetting or restoring plate 45 129, mounted for up-and-down movement by pivoted connections to arms of bell-crank 130 (Fig. 1), journaled on shafts 131, said bell-crank being connected to rotate together by links 132. A dog 133 is 50 mounted for one-way rotation on the general operator, so that on forward movement thereof, it may snap idly over a lug 134 fixed to the forward of the two shafts 131, but on return movement of said general operator, the dog 133 lifts the lug 134, so as to 55 rotate the said shaft 131 in a counter-clockwise direction, and thus cause an arm 135, secured to said shaft, to elevate the resetting plate 129, and thereby restore all of the 60 pins, which have been set, to their normal positions. The pin restoring mechanism, herein very generally disclosed, is in common use and is fully illustrated and described in prior patents, see, for example, the aforesaid Hanson patent, and Patent No. 1,270,411, granted June 25, 1918, to Frederick A. Hart.

The machine may also be provided (as in the aforesaid Minton patent) with means 65 for disabling the computing mechanism when the typewriter carriage is in a computing zone, that is, in a zone in which the tappet 80 may be caused to engage the jacks 83. When such disabling means is provided, 130

The machine may be provided with means whereby any number key, when depressed, will lock all the others, so as to prevent the depression of a second key until after the first key depressed has been released and restored to normal position. For such purpose (see Figs. 1 and 7), each key is provided with a depending bar 140, which may normally pass between two adjacent members of a series of pendent locking elements 141 secured to the machine frame by pivoted connections 142, the pendants being disposed in series between abutments 143 so spaced, relatively to the sum of the width of said locking pendants, that when any two of said pendants are separated by a bar 140 of any particular key, all the other pendants will be tightly closed, one against another, so as to prevent the depression of any other key. In order that such locking mechanism 80 may be effective on the "0" key, as well as the keys representative of the digits "1" to "9", the "0" key may be placed in line with said digit keys and provided with a similar bar 140. 90

The above-described key-locking mechanism may also be used as means to prevent the depression of a number key when the typewriter carriage has been spaced to a position for writing a comma between the digits of a number to point off the same, or to a position for writing a decimal point. To this end, there may be provided (see Fig. 3) special jacks 150, each connected through a linkage (not fully shown) with a corresponding link 151, (Fig. 1), having a pin-and-slot connection with an arm 152 fast on a rock-shaft 153. Also fast on said rock-shaft 153 is a forwardly extending arm 154 (Figs. 1 and 7), having a wedge-shaped extremity, which may be forced between a pair of the locking elements 141 lying between two keys. When any of the special jacks 150 are engaged by a tappet 80, the rock-shaft 153 will be slightly rotated by 105 one of the arms 152 in a clockwise direction, thus forcing the end of the arm 154 between the adjacent locking elements and crowding all of the elements of the series together, so as to lock all of the number keys and thus 110 prevent their operation. Locking mechanism of the character herein very generally disclosed is in common use, and may be found fully illustrated and described in prior patents, see, for example, the aforesaid Hanson patent, and Patent No. 1,270,411, granted June 25, 1918, to Frederick A. Hart. 115

The machine may also be provided (as in the aforesaid Minton patent) with means 120 for disabling the computing mechanism when the typewriter carriage is in a computing zone, that is, in a zone in which the tappet 80 may be caused to engage the jacks 83. When such disabling means is provided, 125

typewriting may be effected in such a zone without computing. To this end, each arm or block 81 (Figs. 1 and 10) is pivotally attached to the rod 82, and is normally supported at its outer end by a bar 160 at a level such that its tappet 80 may pass below the jacks 83 without engaging and rocking them. To elevate the end of an arm 81 when the carriage enters a computing zone, so as to cause its tappet 80 to engage and rock the jacks, the arm is provided with a roller 161 which mounts and rides along the zone-controlling roller 162 having tapered ends, said roller being mounted between the arms 163 extending from a rock-shaft 164 mounted in brackets secured to the machine frame. The roller 162 may be normally held in the path of the roller 161 by means of a spring 165 connecting one of the arms 163 to the machine frame. As the carriage enters a computing zone, the roller 161 rides up the inclined end of the roller 162, thus camming the end of the arm 81 upward, and causing said arm to rotate sufficiently about the rod 82, to bring the tappet 80 into cooperative relation with the jacks 83. Each arm 81 may be provided with one or more teeth in engaging relation with slots or notches in the bar 160, said teeth and notches serving as means to maintain the adjustment of the arm when in either its normal position or when slightly elevated into its operative position. Each arm 81 may be adjusted along the bar 82 by rotating the same sufficiently to disengage its teeth from the slots or notches in the bar 160, after which said arm may be moved along the bar 82 to a position corresponding with any desired letter-space division of the typewriter scale.

To operate the above-described mechanism so as to disable the computing mechanism when the typewriter carriage is in a computing zone, there may be provided (as in the aforesaid Minton patent) a non-add key 166 (Fig. 1) mounted on the forward end of a thrust bar 167 pivotally connected to a lever 168, one arm of which may be caused to engage and move an arm 169 fast upon the rock-shaft 164, so as to impart a slight clockwise rotation thereof against the influence of the spring 165, and thus move the roller 162 out of the path of the rollers 161. The operation of the non-add key 166, therefore, disables the carriage-controlled denomination-selecting mechanism comprising the tappets 80, jacks 83, and parts controlled thereby.

Machines of the type disclosed in the aforesaid patents to Hanson and Minton, and in the Thornton Patent, No. 1,283,360, granted October 29, 1918, and referred to in said Minton patent, are provided with means whereby the machine may be used to subtract, or, in other words, to effect the

geometric addition of negative quantities as well as to add positive quantities. In the particular machines to which reference has been made, this subtraction is accomplished by adding complements of digits of the numbers to be subtracted in a manner now well known to those skilled in the art. This is effected by providing the machine with adjustable index-setting or pin-setting mechanism and by providing means for varying the co-operative relation between the number keys and such mechanism, so that a given number key may set one indexing pin when indexing a number to be added, and so that the same number key may set a different or complementary pin when indexing a number to be subtracted. In such a machine, the number wheels rotate in the same direction for subtraction as for addition, the extent of rotation only being different.

For accomplishing the last-mentioned purpose, the shafts 62 (Fig. 1) are mounted for endwise movement in the machine frame, so that their arms 64, which are normally connected with pin-setting linkages 63 in such manner that the number keys may cause pins to be set in accordance with the digits represented by said keys, may be disconnected from said linkages, and other arms on said shafts may be moved into engaging relation with said linkages in a different relation, so that said number keys may cause pins to be set in accordance with the complements of the digits represented by said keys. In this changed relation, the "1" key may set an "8" pin, the "2" key a "7" pin, the "3" key a "6" pin, etc. To accomplish the above-indicated results, the shafts 62 may be shifted in unison from the addition position, indicated in Fig. 1, to the subtraction position, indicated in Fig. 2, by a universal shift bar 180 (Fig. 1), which engages notched portions of said shafts. The parts of the subtraction-setting mechanism thus far generally disclosed are fully illustrated and described in the aforesaid Hanson patent.

The universal shift bar is pivoted at its upper edge, and is provided with an arm 181 (Fig. 1), which has a pin-and-slot connection with an arm 182 on a rock shaft 183. The rock shaft 183 is provided with a second arm 184, having a pin-and-slot connection with a subtraction-setting bar 185, mounted for endwise movement in the machine frame.

The subtraction-setting bar 185 (Fig. 1) is normally locked in its forward position against the tension of a spring 186 by a detent 187 engaging a notched portion of said bar. The detent may be caused to release said bar by pressing forward a subtraction key 188, mounted on the forward end of a thrust rod 189, pivotally connected to an arm 190, rigidly secured to a rock

shaft 191, to which said detent 187 is also fixedly attached, and by means of which it may be moved out of engagement with said key bar. This part of the subtraction-setting mechanism, in the form herein generally set forth, is fully illustrated and described in the aforesaid Minton patent.

The means for setting the machine for subtraction by complementary addition should 10 also include means for setting all of the "9" pins when the subtraction key is pressed forward. This is for the reason, as is now well known to those skilled in the art, that whenever a "0" appears in any denominational order of a number to be computed, the "9" pin should be set on the rack bar of corresponding denomination to prepare the same for a nine-step advancement. It is also necessary that the "9" pins on all rack 20 bars of denominational orders higher than that of the first digit of the number to be subtracted should be set. But since the depression of the "0" key to print the "0" does not affect the computing mechanism, and 25 since no keys are operated by which pins on the bars of higher order than that of the first digit of said number can be set, it is necessary to provide other means for setting the pins, which, in machines of the character 30 herein described, is included as a part of the subtraction-setting mechanism. Means is also provided whereby, on the depression of any of the digit keys from "1" to "9", the set "9" pin of corresponding denominational order will be restored to its normal 35 position.

For the purpose of accomplishing the above-indicated results, each of the "9" pins is connected to a setting and restoring lever 40 192 (see Fig. 2), and there is provided a special "9" pin-setting bar 193 which is depressed when the subtraction-setting bar 185 is moved rearwardly by mechanism, not shown herein, but which is fully illustrated 45 and described in the aforesaid Minton patent. When said "9" pin-setting bar is thus depressed, it is brought into contact with raised portions 194 (Figs. 2 and 10) on the forward ends of said levers, which are 50 thereby rocked in a counterclockwise direction so as to set the connected "9" pins. There is also provided, as in said Minton patent, a "9" pin-restoring linkage having a 55 resetting bar 195 (Fig. 2), said restoring linkage and bar being similar to the linkages 63 and pin-setting bars 65, heretofore described. Each of the shafts 62 is also provided with an arm similar to the arms 64, which is moved into coöperative relation 60 with the "9" pin-restoring linkage when the subtraction-setting bar 185 is moved rearward, but said arm is normally disconnected from said linkage so that the same will not be operated by the number keys when the 65 machine is set for addition. When any of

the keys, representative of the digits "1" to "9", is depressed to set a pin corresponding to a complementary digit on one of the rack-bars 67, after the machine has been set for subtraction and the "9" pins have therefore 70 been set, as heretofore described, the "9" pin-resetting bar 195 (Fig. 2) will be depressed, so as to engage the upturned rear end 196 of the lever 192 which will have been advanced by the denomination-selecting mechanism into coöperative relation with said bar. Normally, the upturned ends 196 of the levers 192 will stand a little to the rear of the resetting bar 195, so as to be out of coöperative relation therewith, as indicated 80 in Fig. 1. The elevated portions 194 of said levers, on the other hand, are normally positioned so as to be depressed when the "9" pin-setting bar 193 is lowered.

To complete the subtraction-setting mechanism, there is also provided means for imparting an extra step of rotation to the units number wheel at each subtraction operation, the necessity for which is well known and is fully explained in the aforesaid Hanson patent. In this instance, I have very generally indicated, as a means for accomplishing this purpose, the supernumerary bar 197 (Fig. 3), having mounted thereon a trigger or interponent 198, indicated in broken lines in 95 Fig. 2. The supernumerary bar is provided with a pin-advancing portion 199 (Fig. 3), which conforms in size and shape with a recess or cut-away portion 200 of the general operator cross-bar 103. The supernumerary 100 bar 197 is provided with neither rack teeth nor denomination-selecting mechanism, its function being to modify the coöperative relation between the general operator and the units rack bar. If the machine is set for 105 addition, the supernumerary bar remains stationary while the general operator cross-bar 103 moves forward until its pin-advancing portion 199 coincides with the recess 200, at which time the front of the pin-advancing 110 portion 199 will be in alignment with the front or pin-advancing edge of the general operator cross-bar 103. On further movement, the general operator cross-bar 103 and the supernumerary bar will move forward 115 together, and the effect upon a set pin in the units rack bar is not different from that upon set pins of any of the other rack bars. When the machine is set for subtraction, however, the interponent or trigger 198 is 120 set by the "9" pin-setting bar on depression of the subtraction key, so as to effect a different driving engagement from the cross-bar 103 through said interponent to said supernumerary bar, as a result of which the 125 supernumerary bar is moved forward with the front edge of the pin-advancing portion 199 sufficiently ahead of, or in the lead of, the pin-advancing edge of the cross-bar 103 to effect an extra step of movement of the 130

units rack bar; that is, if a "9" pin has been set by the subtraction-setting bar, the units rack bar will be moved forward ten steps instead of nine, or, if an "8", or a "7", or a 5 "6", etc., pin has been set as a result of the depression of a "1", or a "2", or a "3", etc., key, respectively, the rack bar will be advanced nine, or eight, or seven, etc., steps, respectively. This form of extra unit-advancing mechanism is somewhat different 10 from that disclosed in the aforesaid Hanson patent, but is fully illustrated and described in the above-mentioned patent to Thornton. In this case, as in that, since no pin is set 15 by the "9" key when the machine is set for subtraction, there must be a lug (not shown herein, but clearly illustrated and described in said Thornton patent) projecting downwardly from the units racks bar at a distance 20 forward of the "1" pin equal to one step of rack-bar movement, so as to provide for the one-step movement to be imparted to the units rack bar by the driving portion 199 when 9 is to be subtracted in units place. 25 As in the patent last referred to, the trigger or interponent 198 is restored to normal position by the pin-restoring plate 129.

To restore the subtraction-setting bar and parts controlled thereby to their normal positions, so as to re-set the machine for addition, there is provided a lug 210 (Fig. 2), which is engaged by the cross-bar 103 of the general operator, on its forward movement, when running a number to be subtracted 30 into the totalizer, and by which said bar is moved forward against the influence of the spring 186 until the detent 187 reengages the notched portion of said bar.

Machines of the character thus far generally described are in common use, are 40 fully illustrated and described in the patents to which reference has been made, and, *per se*, constitute no part of my invention. Many ancillary parts of the machine, as disclosed 45 in the aforesaid Minton patent, which may be used on a machine with my invention applied thereto, but upon the presence of which it is in no manner dependent, have been omitted for the purpose of simplifying 50 the disclosure. Such omitted parts include the motor for driving the general operator, the automatic motor-starting trips and subtraction-setting trips controlled by the movement of the typewriter carriage, the 55 means for locking the number keys during a subtraction-setting, the means for disabling the motor-starting trips and subtraction-setting trips during the operation of the general operator, the means for disabling 60 the motor-starting trips and automatic subtraction-setting mechanism by the non-add key and by manual means independent of the non-add key, the automatic restoring means for the non-add key, the 65 means for locking the subtraction-setting

mechanism during operation of the general operator, the means for locking the number keys, for closing the sight-opening, and for locking the subtraction-setting mechanism after a number has been indexed so as to 70 warn the operative to set the general operator in action, and the means for holding the subtraction-setting mechanism in set position and for releasing the same at will.

I will now describe the novel features, 75 which, in connection with parts of the machine already described, exemplify one form of my invention.

The number wheels of the totalizer are each provided with two sets of figures, one 80 set, designated 220 (Fig. 5), for exhibiting positive results, and the other set, designated 221, to exhibit negative results. Each set comprises a "0" and the digits "1" to "9", the figures of one set being alternated 85 with those of the other and arranged in inverse order of increasing magnitude. The figures of the different sets may be distinguished from each other, as, for example, by making those of one set black and those 90 of the other set red, as indicated in full and broken lines, respectively. As herein disclosed, two "0"'s are placed together, and the numbers of the sets are so arranged that any digit of one set added first to one and 95 then to the other of its two neighboring digits of the other set will add nine and ten, respectively. This particular arrangement is not a necessary one, but may be varied, the only condition being that the position 100 and operation of the totalizer-index or shutter, hereinafter to be described, are, in certain respects, determined by the particular relative arrangement of the digits of the two sets of figures on the number wheels. 105

In order to positively and selectively direct attention to the figures of one or the other of the two sets on the number wheels from which a reading is to be taken, depending upon whether the result accumulated in the totalizer is positive or negative, there is provided an index which, as herein disclosed, is in the nature of a shield or shutter 230 (Figs. 2, 3, 4, 8, and 9), having a sight-opening 231 of sufficient width to 110 expose one row of characters only on the number wheels. This shutter may be pivotally mounted upon the shaft 232, on which the number wheels are journaled, and so positioned as to lie between the peripheries 115 of the number wheels and the totalizer-casing 102. The sight-opening 101 in said casing is of sufficient width to expose two adjacent rows of figures on the number wheels, and the shutter is capable of shifting so as 120 to expose either row and to conceal the other.

The shutter 230 normally stands in the position indicated in Fig. 8, which is designative of a positive result in the totalizer, 125 130

in which case the upper of the two rows of figures, coincident with the sight-opening 101, is exposed (see Fig. 3). To shift the index or shutter to its position illustrated in Fig. 9, designative of a negative result in the totalizer, and in which it exposes the lower of the two rows coincident with the sight-opening 101, there is provided a rotary actuator, here shown as a disk 233, which may be, in many respects, similar to the totalizer number wheels, and may be journaled on the same shaft 232, on which said number wheels are journaled. This shutter-operating disk may be provided with a cam 234 to coöperate with a cam-follower in the nature of a lever 235, pivotally secured, by means of a bracket 236, to the under side of the machine casing 102; and said lever may be connected by a link 237 to the index or shutter 230. A spring 238 normally tends to hold the follower 235 against the cam. The relative position of the sight-opening 231 in the index to the red and black numbers on the totalizer 25 wheels is indicated diagrammatically in Figs. 8 and 9 by the alternated full and broken line figures 239, spaced about the periphery of the disk.

As in the case of the number wheels, the shutter-operating disk 233 is connected, through a one-way driving clutch, with a pinion 240 having teeth in engagement with teeth on a shutter-operating rack-bar or driving element 241, similar to the rack-bars 67 for driving the totalizer number wheels. This rack-bar, however, differs from the totalizer rack-bars, in that it is provided with but two indexing devices instead of nine. One of the said indexing devices is a settable pin 242, corresponding in every way with the "8" pin of a totalizer rack-bar, and provides, when set, for a rack-bar movement of eight steps by the general-operator cross-bar 103. The other indexing device 243 of the shutter-operating rack-bar 241 has an upstanding setting member 244, in alinement with the "1" pins of the totalizer rack-bars, and adapted to be set by the "1" pin-setting bar 65; but said indexing device is provided with a contact surface 245 in line with the rear surfaces of the "2" pins of the number-wheel-advancing rack-bars, so as to provide for a two-step movement of the shutter-operating rack-bar by the cross-bar 103 when the indexing device 243 has been set.

As hereinafter described, the indexing devices of the shutter-operating rack-bar are set in alternation. A setting of the indexing device 242 causes the general operator to advance the rack-bar eight steps and shift the parts of the mechanism from the positions indicated in Fig. 8 to those indicated in Fig. 9, changing the position of the 60 shutter from its positive designating posi-

tion to its negative designating position. A subsequent setting of the indexing device 243 causes the general operator to advance the index-operating rack-bar two steps, so as to complete the rotation of the 70 shutter-operating disk, thus returning the shutter to its normal position, designative of a positive result, as represented in Fig. 4. Fig. 8 shows the same parts of the mechanism after the general operator has been 75 restored and the indexing devices have been restored by the pin-resetting plate 129.

In the form herein disclosed, there may be provided a spring detent 246 (Fig. 8), having a spherical projection 247, adapted 80 for engagement with either of two depressions 248 in the indexing device 243, to yieldably maintain the same either in its set or in its normal position.

The indexing devices for the rack-bar 85 241, like those of the totalizer rack-bars, are normally out of alinement with the pin-setting bars 65, so that a depression of said bars is normally ineffective on said indexing devices. The shutter-operating rack- 90 bar, however, has no jack 83 or other denomination-selecting mechanism to be controlled by the tappet 80 for bringing its indexing devices into setting relation with the pin-setting bars 65, as is the case with 95 the totalizer rack-bars. The setting of the indexing devices of the shutter-operating rack-bar is, therefore, independent of the letter-spacing movements of the typewriter carriage.

For a purpose hereinafter made clear, the indexing devices of the shutter-operating rack-bar are brought into setting relation with the pin-setting bars 65 by the case-shift mechanism when operated to shift the 105 platen of the typewriter to upper-case position. To this end, as herein disclosed (see Figs. 2 and 10), the shift-key-lever 45 is connected, by means of a thrust-rod or a link 260, to an arm 261 fast on a rock-shaft 262. 110 A second arm 263, fixedly secured to said rock-shaft, is connected by a link or thrust-rod 264 to one arm of a bell-crank 265, the other arm of which is adapted to engage a pin 266 on the index-operating rack-bar 241, 115 so that, on depression of the shift-key 44, the bell-crank will be rocked and the rack-bar will be shifted slightly forward to bring its indexing devices 242 and 243 into setting relation with the "8" and "1" pin-setting bars 65, respectively. With the mechanism thus far disclosed, it will be apparent that if the machine is set for subtraction and the case-shift key is depressed, a depression of the "1" key will cause the pin 120 242 on the rack-bar 241 to be set, so that, on operation of the general operator, the totalizer-index or shutter will be shifted to its position designative of a negative result. It will also be apparent that if, with the ma- 130

chine set for addition, the shift-key is again depressed, a depression of the "1" key will cause the indexing device 243 of the rack-bar 241 to be set, so that on the next operation of the general operator, the shutter will be restored to its position designative of a positive result.

Before leaving the shutter-operating mechanism, it should be observed that the 10 shutter-operating disk or actuator is not provided with any figures; that it may be concealed underneath the machine casing; and that it is not connected by carrying mechanism with the number wheel of highest denominational order, or with any other number wheel of the totalizer.

As already explained, it is only necessary to cause the totalizer-index or shutter to be shifted, as above described, after a computation has been effected which causes the machine to pass through zero, and provided it is desired to take a reading. It has also been explained that when the machine has been caused to pass through zero, by adding 25 a negative quantity which changes the result in the totalizer from positive to negative, it is necessary to add an additional negative unit, or fugitive unit as it is called, to the number previously accumulated in 30 the totalizer. And it has also been explained that when the machine has been caused to pass through zero, by adding a positive quantity which changes the result in the totalizer from negative to positive, 35 it is necessary to add an additional positive unit to the number previously accumulated in the totalizer. It follows that the fugitive unit is always to be added concomitantly with the shifting of the shutter; that the 40 unit to be added must be negative in character when the shutter is shifted from its position designative of a positive result to its position designative of a negative result, and that the unit to be added must be positive in character when the shutter is shifted from its position designative of a negative result to that designative of a positive result.

For the purpose last mentioned, special 50 means is provided for effecting a setting relation between the indexing devices or pins on the units rack-bar and the pin-setting bars 65, when the case-shift mechanism is operated to shift the typewriter platen to 55 upper-case position. Referring to Figs. 2 and 10, the case-shift-key-lever 45 is connected, through a thrust rod or link 280, with an arm 281, fast on a rock-shaft 282. Fixedly secured to said rock-shaft 282 is 60 another arm 283, connected, through a pin-and-slot connection, with one end of a link or thrust rod 284, the other end of which is connected with an arm 285, projecting from the bell-crank 90 of the denomination-selecting mechanism, by which the units rack-

bar is advanced to its coöperative setting relation with the pin-setting bars 65. It will thus be seen that if the machine is set for subtraction and the case-shift-key is depressed, a depression of the "1" key will 70 cause the "8" pin, that is, the one complementary to the "1" pin, to be set, so as to cause a negative unit to be added when the general operator is operated. On the other hand, if the machine is set for addition and the case-shift-key is depressed, a depression of the "1" key will cause the "1" pin to 75 be set, and thus cause a positive unit to be added when the general operator is operated.

The pin-and-slot connection between the arm 283 and the link 284 permits free movement of the bell-crank 90 of units denomination by the carriage-controlled denomination-selecting mechanism, during ordinary computing operations, without interference by the connection from the case-shift-key.

Unless some means is provided for disabling other parts of the computing mechanism, when setting the shutter-operating mechanism and fugitive-unit-inserting mechanism, it would be necessary to avoid operating such mechanism without first moving the letter-spacing carriage of the 95 typewriter out of a computing zone. Otherwise, the fugitive unit might be incorrectly inserted into a number-wheel of an order higher than units order. Such necessity of spacing the typewriter carriage beyond a computing zone would in no manner defeat the purpose of the invention, since it would be merely necessary for the operative to remember that the complete number, which causes the machine to pass through zero, 100 should be entered before attempting to operate the shutter. On writing the digits in units order, the machine would pass out of the computing zone, after which the shutter-operating and fugitive-unit-inserting 110 mechanism might be safely operated with no danger of giving incorrect results. Means for disabling other parts of the computing mechanism, when the shutter is to be shifted and the fugitive unit inserted, may, however, be very readily supplied, so that such mechanism may be operated, irrespective of the letter-spacing position of the typewriter carriage, as will now be described.

Fixedly secured to the rock-shaft 262 120 (Figs. 2 and 10), is an arm 290, connected, by a link 291, with one end of a lever 292, pivotally connected at 293 to the machine frame. The other arm of the lever 292 has contact with an arm 294, fixedly attached 125 to the rock-shaft 164, so that, on depression of the case-shift-key 44, the lever 292 will be rocked, and thus caused to cam the arm 294 upwardly, so as to rotate the rock-shaft 164, on which the tappet-positioning roller 130

162 is mounted, and thus move said roller out of the path of the rollers 161. It follows that when said case-shift-key is depressed, none of the jacks 83 and denomination-selecting mechanism, controlled thereby, can be operated by the tappets 80, and the number-keys are incapable of setting pins or indexing devices on any of the rack-bars, except the shutter-operating rack-bar, 10 and the units rack-bar, which are moved into setting relation by the above-described mechanism, controlled by the case-shift-mechanism. With this disabling mechanism added to the machine, the case-shift-key and the "1" number-key may be operated to set the indexing devices, for the operation of the shutter and for the insertion of the fugitive unit, independently of the position of the typewriter carriage, without any possibility of introducing the fugitive unit in the wrong number-wheel. Unless some means is also provided for locking the keys other than the "1" key, when the shutter is to be shifted and the fugitive unit added, the operative might make an error by depressing the wrong number-key, as a result of which the shutter would not be shifted and a unit other than "1" would be inserted in the totalizer. As 30 a means for preventing the possibility of such faulty operation, mechanism may be provided for locking all the keys other than the "1" key when the case-shift-key is depressed. For this purpose, there is rigidly secured to the rock-shaft 282 (Figs. 1 and 10), an arm 300, connected to one end of a link 301, the other end of which is connected to an arm 302 of a bell-crank 303, journaled on the rock-shaft 153. Depression of the 35 case-shift-key 44 will thus cause the bell-crank 303 to be rocked about said shaft 153, so as to force an arm 304 (Figs. 10 and 7) of said bell-crank between an abutment 305, fixed to the machine frame, and a cam member 306 on the right-hand locking pendant 141 of the pair of pendants which are associated with the "1" key. By this means, 40 all of the pendants to the right of the "1" key are crowded together, so as to lock all other keys, but the pair of pendants associated with the "1" key may be readily separated by its bar 140, thus permitting said key to be operated, to the exclusion of all others. 45 The machine, equipped as above described, may be operated for ordinary arithmetical additions and subtractions exactly as those of the prior art are operated, the readings being taken from the totalizer through the 50 sight-opening of the index or shutter 230, when in the position illustrated in Figs. 1, 4 and 8. At such times, a "0" will always appear at the sight-opening on the highest number-wheel, which indicates that the result accumulated in the totalizer is positive. 55

If, at any time, when the operative attempts to take a reading, the "0" has disappeared and has been replaced by a "9", the operative will immediately know that an over-draft has been effected, which has caused the 70 machine to pass through zero, and that the result registered in the totalizer is negative. In other words, the aggregate of the negative quantities, previously added in the totalizer, exceeds the aggregate of the positive quantities, and the result appearing at the sight-opening is not the true result. Under such circumstances, the operative sets the machine for subtraction, if it is not already so set, depresses the case-shift-key and the "1" number-key, and operates the general operator, as a result of which the totalizer-index or shutter will be shifted to the position indicated in Fig. 9, and an extra negative unit, the fugitive unit, will 80 be run into the totalizer. The result will then be correctly indicated by the figures which appear at the sight-opening, and may be read therefrom directly. After the shifting of the index, a "0" will again appear, 85 in place of the "9", on the highest number-wheel. If further computations are such that the result accumulated in the totalizer remains negative, no further attention need be paid to the shutter-operating mechanism. 90 If, however, the machine should pass back through zero, in the opposite direction, as would be the case should the total accumulated become positive, the "0" on the highest number-wheel, displayed through the 100 opening in the shutter in the latter's shifted or negative position, would again disappear and a "9" take its place. The operative, observing this, must then, with the machine set for addition, again depress the typewriter case-shift-key and the "1" number-key and operate the general operator, as a 105 result of which the shutter will be restored to its position designative of a positive result, indicated in Figs. 1, 4 and 8, after 110 which the correct positive total may be read at the sight-opening.

It will be apparent that the printing of a "1" on the work-sheet, when the "1" number-key is depressed, for the purpose of 115 causing the shutter to be shifted and the fugitive unit to be added, would be confusing and unsightly. For this reason, the type-bar 310 (Fig. 2), which has thereon the type 311, for printing the digit "1" in lower 120 case, is not provided with any type for printing in upper case.

In view of the fact that the appearance of a "9" on the number-wheel of highest order is used as a signal or warning, to indicate 125 that the machine has been caused to pass through zero, it may be desirable, in order to avoid possibility of error, that said number-wheel be incapable of being advanced directly from "0" to "9," through the digits 130

"1," "2," "3," and so forth, up to "9," at a single computing operation, as would be the case if a large number, having a digit "9" of a denominational order corresponding to 5 that of the highest number-wheel, were attempted to be added. To this end, the number-wheel of highest order is not provided with a jack 83, to be operated by a tappet 80, nor is it provided with any denominational-selecting mechanism. The pins of the 10 rack-bar for the number-wheel of highest denominational order are also omitted, with the exception of the "9" pin, which is essential to the operation of the machine, when set for subtraction. The machine is not, therefore, adapted for the addition of numbers having as many digits as there are number-wheels of the totalizer. Such numbers would be regarded as exceeding its capacity. 15 The highest number-wheel is not, however, limited in its use to that of being a mere indicator of the character of the results, but is, in every proper sense of the term, a number-wheel. Carrying mechanism is provided for 20 carrying from the number-wheel of next lower order to the highest number-wheel, so that the totalizer may be caused to accumulate totals having as many digits as there are number-wheels in the totalizer. When 25 so operated, the highest number-wheel would be caused to advance from "0" to "1," or from "1" to "2," or from "2" to "3," and so forth, only as a result of a large number of additions. When so operated, the operative 30 would not confuse the turning of the highest number-wheel from "0" to "9" by gradually passing in this manner through all the digits "1," "2," "3," and so forth, which would indicate that the capacity of the machine has been exceeded, with the change 35 from "0" directly to "9," when the machine has been caused to pass through zero by an overdraft.

If desired, the black "9" on the highest 40 number-wheel may be replaced by some special character indicative of a negative result, as a minus sign 315, Fig. 6, and likewise the red "9" may be replaced by a special character indicative of a positive result, 45 as a plus sign 316.

With such characters substituted, the appearance of the minus sign would indicate to the operative that the machine has passed through zero, and that the result accumulated 50 in the totalizer is negative. The operation of the mechanism for shifting the shutter and for adding the fugitive unit will cause the minus sign to disappear. Should the machine subsequently pass 55 through zero in the opposite direction, the plus sign would be caused to appear, which would apprise the operative of the necessity of again causing the shutter to be shifted and the fugitive unit to be added. The appearance 60 of these signs would always indi-

cate the necessity of shifting the shutter before taking a reading, and the character of the sign would indicate the proper setting of the machine, as for addition or subtraction, so as to insure the addition of a fugitive 70 unit of the proper character.

Should it be desired to provide the machine with two or more totalizers, as in the case of the aforesaid Hart Patent, No. 1,270,411, it will be apparent that each computing mechanism might be provided with its own individual key 44, to control the setting of its shutter-operating and fugitive-unit-inserting mechanism, and that each of 75 said keys might be provided with an arm 46, 80 to operate the shift-frame of the common typewriter mechanism.

Variations may be resorted to within the scope of the invention, and portions of the improvements may be used without others. 85

Having thus described my invention, I claim:

1. In a computing machine, in combination, an algebraic totalizer having a shiftable index, actuating mechanism for said totalizer, shifting mechanism for said index, and manually settable means, capable of being rendered effective at the will of the operative, for establishing an operating connection between a part of said actuating 90 mechanism and said index-shifting mechanism, through which said index may be shifted.

2. In a computing machine, in combination, an algebraic totalizer having a shiftable index, actuating mechanism for said totalizer, shifting mechanism for said index, and key-controlled setting mechanism effective, when set, to establish an operating connection between a part of said actuating 100 mechanism and said index-shifting mechanism, through which said index may be shifted. 105

3. In a computing machine, in combination, an algebraic totalizer having a shiftable index, actuating mechanism for said totalizer, including a general operator, shifting mechanism for said index, and manually settable means, capable of being rendered effective at the will of the operative, for establishing an operating connection between said general operator and said index-shifting mechanism, through which 110 said index may be shifted. 115

4. In a combined typewriting and computing machine, in combination, a typewriting mechanism, including number-keys and a case-shift-key, an algebraic computing mechanism, including a shiftable index, and means, controlled in part by said case-shift-key and in part by one of said number-keys for shifting said index. 120 125

5. In a combined typewriting and computing machine, in combination, a typewriting mechanism, including number-keys and 130

- tion, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, and manually settable means, controlled in part by said subtraction-setting mechanism, for rendering said operating connection effective, so that said index will be shifted as a result of an actuation of said general operator.
15. 17. In a combined typewriting and computing machine, in combination, a typewriting mechanism, including number-keys, an algebraic totalizer having a shiftable index, actuating mechanism for said totalizer, including a general operator, shifting mechanism for said index, normally ineffective means for establishing an operating connection between said general operator and said index-shifting mechanism, and manually settable means, controlled in part by one of said number-keys, for rendering said operating connection effective, so that said index will be shifted as a result of an actuation by said general operator.
20. 18. In a combined typewriting and computing machine, in combination, a typewriting mechanism, including case-shift mechanism, an algebraic totalizer having a shiftable index, actuating mechanism for said totalizer, including a general operator, shifting mechanism for said index, normally ineffective means for establishing an operating connection between said general operator and said index-shifting mechanism, and means, controlled in part by said case-shift mechanism, for rendering said operating connection effective, so that said index will be shifted as a result of an actuation of said general operator.
25. 19. In a combined typewriting and computing machine, in combination, a typewriting mechanism, including number-keys and case-shift mechanism, an algebraic totalizer having a shiftable index, actuating mechanism for said totalizer, including a general operator, shifting mechanism for said index, normally ineffective means for establishing an operating connection between said general operator and said index-shifting mechanism, and means, controlled in part by a concomitant operation of said case-shift mechanism and one of said number-keys, for rendering said operating connection effective, so that said index will be shifted as a result of an actuation of said general operator.
30. 20. In a combined typewriting and computing machine, in combination, typewriting mechanism, including number-keys, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, and manually settable means, controlled in part by said subtraction-setting mechanism, and in part by one of said number-keys, for rendering said operating connection effective, so that said index will be shifted as the result of an actuation of said general operator; the direction of shift being determined by the setting of the subtraction-setting mechanism.
35. 21. In a combined typewriting and computing machine, in combination, a typewriting mechanism, including case-shift mechanism, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, and means, controlled in part by said subtraction-setting mechanism, and in part by said case-shift mechanism, for rendering said operating connection effective, so that said index will be shifted as the result of an actuation of said general operator, the direction of shift being determined by the setting of the subtraction-setting mechanism.
40. 22. In a combined typewriting and computing machine, in combination, a typewriting mechanism, including number-keys and case-shift mechanism, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, and means, controlled in part by said subtraction-setting mechanism, and in part by a concomitant operation of said case-shift mechanism and one of said number-keys, for rendering said operating connection effective, so that said index will be shifted as the result of an actuation of said general operator, the direction of shift being determined by the setting of the subtraction-setting mechanism.
45. 23. In a combined typewriting and computing machine, in combination, a typewriting mechanism, including case-shift mechanism, an algebraic computing mechanism, and means, controlled in part by said case-shift mechanism, for adding a unit in the lowest denominational order of said computing mechanism.
50. 24. In a combined typewriting and computing machine, in combination, a type-

writing mechanism, including number-keys and case-shift mechanism, an algebraic computing mechanism, and means, controlled in part by a concomitant operation 5 of said case-shift mechanism and one of said number-keys, for inserting a unit in the lowest denominational order of said computing mechanism.

25. In a combined typewriting and computing machine, in combination, a typewriting mechanism, including case-shift mechanism, an algebraic computing mechanism, including subtraction-setting mechanism, and means, controlled in part by said 10 case-shift mechanism and in part by said subtraction-setting mechanism, for adding either a positive or a negative unit in the lowest denominational order of said computing mechanism, the setting of said subtraction-setting mechanism being determinative of the character of the unit added.

26. In a combined typewriting and computing machine, in combination, a typewriting mechanism, including number-keys 25 and a letter-spacing carriage, controlled in its letter-spacing movements by the operation of said keys, an algebraic computing mechanism, means, controlled in part by letter-spacing movements of said carriage, 30 in accordance with the operation of said number-keys, for adding numbers in said computing machine, and means, controlled in part by one of said keys, irrespective of the letter-spacing position of said carriage, 35 for adding a unit in the lowest denominational order of said computing mechanism.

27. In a combined typewriting and computing machine, in combination, a typewriting mechanism, including a letter-spacing carriage, a platen mounted in said carriage, and case-shift mechanism for said platen, an algebraic computing mechanism, means, controlled in part by letter-spacing movements of said carriage, for adding 40 numbers in said computing machine, and means, controlled in part by said case-shift mechanism, for adding a unit in the lowest denominational order of said computing mechanism, irrespective of the letter-space 45 position of said carriage.

28. In a combined typewriting and computing machine, in combination, a typewriting mechanism, including number-keys, a letter-spacing carriage, controlled in its 50 letter-spacing movements by the operation of said keys, a platen mounted in said carriage, and case-shift mechanism for said platen, an algebraic computing mechanism, means, controlled in part by letter-spacing 55 movements of said carriage, in accordance with the operation of said number-keys, for adding numbers in said computing mechanism, and means, controlled in part by a concomitant operation of said case-shift mechanism 60 and one of said number-keys, for inserting typewriting and computing mechanism and one of said number-keys.

irrespective of the letter-space position of said carriage, for adding a unit in the lowest denominational order of said computing mechanism.

29. In a combined typewriting and computing machine, in combination, a typewriting mechanism, including case-shift mechanism, an algebraic computing mechanism, including subtraction-setting mechanism, and means, controlled in part by said case-shift mechanism and in part by said subtraction-setting mechanism, for adding either a positive or a negative unit in the lowest denominational order of said computing mechanism, the character of the 70 number added being dependent upon the setting of said subtraction-setting mechanism.

30. In a combined typewriting and computing machine, in combination, a typewriting mechanism, including number-keys, an algebraic computing mechanism, including a shiftable index, and means, controlled in part by one of said number-keys, for shifting said index, and for inserting a unit in 75 the lowest denominational order of said computing mechanism, at the will of the operative.

31. In a combined typewriting and computing machine, in combination, a typewriting mechanism, including case-shift mechanism, an algebraic computing mechanism, including a shiftable index, and means, controlled in part by said case-shift mechanism, for shifting said index, and for inserting a 80 unit in the lowest denominational order of said computing mechanism.

32. In a combined typewriting and computing machine, in combination, a typewriting mechanism, including number-keys, and case-shift mechanism, an algebraic computing mechanism, including a shiftable index, and means, controlled in part by a concomitant operation of said case-shift mechanism and one of said number-keys, for shifting 90 said index, and for inserting a unit in the lowest denominational order of said computing mechanism.

33. In a combined typewriting and computing machine, in combination, a typewriting mechanism, including number-keys, an algebraic computing mechanism, including subtraction-setting mechanism, and a shiftable index, and means, controlled in part by one of said number-keys and in part by said 100 subtraction-setting mechanism, and available at the will of the operative, for shifting said index, and for inserting either a positive or a negative unit in the lowest denominational order of said computing mechanism, the character of the unit added and the change of position of the index being determined by the setting of said subtraction-setting mechanism.

34. In a combined typewriting and com-

puting machine, in combination, a typewriting mechanism, including case-shift mechanism, an algebraic computing mechanism, including subtraction-setting mechanism and a shiftable index, and means, controlled in part by said case-shift mechanism and in part by said subtraction-setting mechanism, for shifting said index, and for inserting either a positive or a negative unit in the lowest denominational order of said computing mechanism, the change of position of said index and the character of the unit added being determined by the setting of the subtraction-setting mechanism.

35. In a combined typewriting and computing machine, in combination, a typewriting mechanism, including number-keys and case-shift mechanism, an algebraic computing mechanism, including subtraction-setting mechanism and a shiftable index, and means, controlled in part by a concomitant operation of said case-shift mechanism and one of said number-keys, and in part by said subtraction-setting mechanism, for shifting said index, and for adding either a positive or a negative unit in the lowest denominational order of said computing mechanism, the change of position of said index and the character of the number added being dependent upon the setting of said subtraction-setting mechanism.

36. In a combined typewriting and computing machine, in combination, a typewriting mechanism, including number-keys, an algebraic totalizer having a shiftable index, actuating mechanism for said totalizer, including a general operator, shifting mechanism for said index, normally ineffective means for establishing an operating connection between said general operator and said index-shifting mechanism, and means, controlled in part by one of said number-keys, for effecting a setting of a part of said totalizer-actuating mechanism to add one unit in the lowest denominational order of said totalizer, and for rendering said operating connection effective, so that said index will be shifted and a unit added as a result of an actuation of said general operator.

37. In a combined typewriting and computing machine, in combination, a typewriting mechanism, including case-shift mechanism, an algebraic totalizer having a shiftable index, actuating mechanism for said totalizer, including a general operator, shifting mechanism for said index, normally ineffective means for establishing an operating connection between said general operator and said index-shifting mechanism, and means, controlled in part by said case-shift mechanism, for effecting a setting of a part of said totalizer-actuating mechanism to add one unit in the lowest denominational order of said totalizer, and for rendering said operating connection effective, so that said

index will be shifted and a unit added as a result of an actuation of said general operator.

38. In a combined typewriting and computing machine, in combination, a typewriting mechanism, including case-shift mechanism and a set of number-keys, an algebraic totalizer having a shiftable index, actuating mechanism for said totalizer, including a general operator, shifting mechanism for said index, normally ineffective means for establishing an operating connection between said general operator and said index-shifting mechanism, and means, controlled in part by a concomitant operation of said case-shift mechanism and one of said number-keys, for effecting a setting of a part of said totalizer-actuating mechanism to add one unit in the lowest denominational order of said totalizer, and for rendering said operating connection effective, so that said index will be shifted and a unit added as a result of an actuation of said general operator.

39. In a combined typewriting and computing machine, in combination, a typewriting mechanism, including number-keys, an algebraic totalizer having a shiftable index, actuating mechanism for said totalizer, including subtraction-setting mechanism and a general operator, shifting mechanism for said index, normally ineffective means for establishing an operating connection between said general operator and said index shifting mechanism, and means, controlled in part by one of said number-keys and in part by said subtraction-setting mechanism, for effecting a setting of a part of said totalizer-actuating mechanism to add either a positive or a negative unit in the lowest denominational order of said totalizer, and for rendering said operating connection effective, so that said index will be shifted and the unit added as a result of an actuation of said general operator, the change of position of said index and the character of the unit added being determined by the setting of said subtraction-setting mechanism. 100 105 110

40. In a combined typewriting and computing machine, in combination, a typewriting mechanism, including case-shift mechanism, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, and means, controlled in part by said case-shift mechanism and in part by said subtraction-setting mechanism, for effecting a setting of a part of said totalizer-actuating mechanism to add either a positive or a negative unit in the lowest denominational order of said total- 115 120 125 130

izer, and for rendering said operating connection effective, so that said index will be shifted and the unit added as a result of an actuation of said general operator, the 5 change of position of the index and the character of the unit added being determined by the setting of said subtraction-setting mechanism.

41. In a combined typewriting and computing machine, in combination, a typewriting mechanism, including number-keys and case-shift mechanism, an algebraic totalizer having a shiftable index, actuating mechanism for said totalizer, including subtraction-setting mechanism and a general operator, shifting mechanism for said index, normally ineffective means for establishing an operating connection between said general operator and said index-shifting mechanism, 10 and means, controlled in part by said subtraction-setting mechanism and in part by a concomitant operation of said case-shift mechanism and one of said number-keys, for effecting a setting of a part of said totalizer-actuating mechanism to add either a positive or a negative unit in the lowest denominational order of said totalizer, and for rendering said operating connection effective, so that said index will be shifted and the 15 unit added as a result of an actuation of said general operator, the change of position of the index and the character of the unit added being determined by the setting of said subtraction-setting mechanism.

35 42. A number wheel for a computing machine, having thereon a "0," the digits "1" to "8," respectively, and a plus sign in the position usually occupied by a "9."

43. A number wheel for a computing machine, having thereon a "0," the digits "1" to "8," respectively, and a minus sign in the position usually occupied by a "9."

44. A number wheel for a computing machine, having thereon two sets of characters, 40 those of one set alternating with those of the other and arranged in inverse order, the characters of one set comprising a "0," the digits "1" to "8," inclusive, and a plus sign, and those of the other set comprising a "0," 45 the digits "1" to "8," inclusive, and a minus sign.

45. A number wheel for a computing machine, having thereon, at equally spaced intervals, in succession, a plus sign, a "0," and 50 a "1" followed by a series of digits increasing by unity.

46. A number wheel for a computing machine, having thereon, at equally spaced intervals, in succession, a minus sign, a "0," and 55 a "1" followed by a succession of digits increasing by unity.

47. A number wheel for a computing machine, having thereon two sets of characters, those of one set alternating with those of the other, and arranged in inverse order, the 60

characters of one set comprising a plus sign, a "0," and a "1" followed by a succession of digits increasing by unity, and those of the other set comprising a minus sign, a "0" and a "1" followed by a succession of digits increasing by unity. 70

48. In a computing machine, in combination, an algebraic totalizer, actuating mechanism for said totalizer including number keys, subtraction-setting mechanism, and a 75 general operator, a shiftable index for said totalizer, actuating mechanism for said index, means including a settable device through which said general operator may shift said index from a position designative of a positive result to a position designative of a negative result, a setting device actuatable by one of said keys, and means whereby said setting device may be made effective on said settable device when the 80 machine is set for subtraction.

49. In a computing machine, in combination, an algebraic totalizer, actuating mechanism for said totalizer including number keys, subtraction-setting mechanism, and a 90 general operator, a shiftable index for said totalizer, actuating mechanism for said index, settable means through which, when set, said general operator may shift said index from its position designative of a negative 95 result to its position designative of a positive result, a setting device actuatable by one of said keys, and means whereby said setting device may be made effective on said settable means when the machine is set for addition. 100

50. In a computing machine, in combination, an algebraic totalizer, actuating mechanism for said totalizer including number keys, subtraction-setting mechanism, and a 105 general operator, a shiftable index for said totalizer, actuating mechanism for said index, a setting device operable by one of said number keys, settable means through which, when set, said general operator may shift 110 said index from a position designative of a positive result to a position designative of a negative result, settable means through which, when set, said general operator may restore said index to its position designative of a positive result, and means whereby said setting device may be rendered effective with respect to the first-mentioned settable means when the machine is set for subtraction and with respect to the other when the 115 machine is set for addition.

51. In a computing machine, in combination, an algebraic totalizer, actuating mechanism for said totalizer including digit-indexing devices, a general operator, a set of 125 number keys, index-setting devices controlled by said number keys, subtraction-setting mechanism to vary the operative relation between said number keys and their index-setting devices, a shiftable index for 130

said totalizer, and shifting mechanism for said index comprising settable means capable of being set by the index-setting device controlled by the "1" key when the machine 5 is set for subtraction to effect an operating connection through which said general operator may shift said index from a position designative of a positive result to one designative of a negative result, settable means 10 capable of being set by the index-setting device controlled by the same key when the machine is set for addition to effect an operating connection through which said general operator may restore said index to its 15 position designative of a positive result, and means whereby the index-setting device controlled by the "1" key may be made effective on the first-mentioned settable means or on the other in accordance with the setting 20 of the machine for subtraction or addition.

52. In a combined typewriting and computing machine, in combination, a typewriting mechanism including number keys and a case-shift mechanism, an algebraic totalizer, 25 actuating mechanism for said totalizer including digit-indexing devices, a general operator, index-setting mechanism controlled by said number keys, subtraction-setting mechanism to vary the coöperative relation 30 between said number keys and the index-setting mechanism, a shiftable index for said totalizer, shifting mechanism for said index, settable means for said shifting mechanism capable of being set by parts of the 35 index-setting mechanism controlled by the "1" key, to effect operating connections through which said general operator may shift said index from a position designative of a positive result to a position designative 40 of a negative result, and vice versa, the direction of shift being determined by the setting of said subtraction-setting mechanism, said index-setting mechanism being normally ineffective on said settable means of 45 said shifting mechanism, and means, controlled by said case-shift mechanism, for disabling the coöperative setting relation between said number keys and said digit-indexing devices, and for establishing coöp- 50 erative relations between parts of the index-setting mechanism controlled by said "1" key and the settable means for said index-shifting mechanism.

53. In a computing machine, in combination, an algebraic totalizer having an index shiftable to either of two positions, one designative of a positive result, and the other designative of a negative result, actuating mechanism for said totalizer including number keys, subtraction-setting mechanism, and a general operator, operating mechanism for said index including means settable for actuation by the general operator to move said index from a position designative 60 of a positive result to a position designa- 65

native of a negative result, means settable for actuation by the general operator to restore said index to its position designative of a positive result, a setting device operable by one of said number keys, and means 70 whereby said setting device may be made effective on one or the other of said settable means in accordance with the setting of the machine for addition or subtraction.

54. In a computing machine, in combination, an algebraic totalizer, actuating mechanism for said totalizer including digit-indexing devices, a general operator, a set of number keys, index-setting devices controlled by said keys, certain of said keys being capable of operating either an index-setting device representative of a digit, or one representative of a complement of the same digit, subtraction-setting mechanism to vary the relations between said keys and 80 said index-setting devices, a shiftable index for said totalizer, a rotatable actuator for said index, means controlled by said actuator for shifting said index, whereby when said actuator is in one position said index will be caused to designate a positive result, and when said actuator is in another position, said index will be caused to designate a negative result, a driving element for said actuator, settable means on said driving 85 element capable of being set by the complementary digit-indexing device controlled by one of said keys when the machine is set for subtraction, and through which said general operator may cause said driving 90 element to rotate said actuator to its position determinative of a negative designating position of said index, and settable means on said driving element capable of being set by the digit index-setting device 95 controlled by the same key when the machine is set for addition, and through which said general operator may cause said driving element to restore said actuator to its position determinative of a positive designating 100 position of said index.

55. In a computing machine, in combination, an algebraic totalizer having a shiftable index, a rotary actuator for said index, a cam carried by said actuator, and means 115 controlled by said cam for shifting said index, the relation of said parts being such that a rotation of said actuator in one direction will cause said index to be shifted from a position designative of a positive result to 120 a position designative of a negative result, and such that a further rotation of said actuator in the same direction will cause said index to be restored to its position designative of a positive result.

56. In a computing machine, in combination, an algebraic totalizer having a shiftable index, a rotary actuator for said index, a cam carried by said actuator, a lever comprising a follower for said cam, yielding 130

means for holding said follower in coöperative relation with said cam, and a link connecting said lever and said index, the relation of said parts being such that a rotation 5 of said actuator in one direction will cause said index to be shifted from a position designative of a positive result to a position designative of a negative result, and such that a further rotation of said actuator in 10 the same direction will cause said index to be restored to its position designative of a positive result.

57. In a combined typewriting and computing machine, in combination, a typewriting mechanism comprising number keys, a letter-spacing carriage, a platen mounted in said carriage, and case-shift mechanism for said platen, a computing mechanism comprising an algebraic totalizer, actuating mechanism therefor including digit-indexing devices and a general operator, index-setting devices controlled by said keys, said digit-indexing devices being normally out of the effective range of operation of said index-setting devices, denomination-selecting mechanism controlled in accordance with the letter-spacing movements of said carriage for establishing setting relations between said index-setting devices and said digit-indexing devices of different denominational orders in succession, and means controlled by said case-shift mechanism for disabling said denomination-selecting mechanism and for establishing a setting relation 30 between said index-setting devices and said digit-indexing devices of units order, so that on concomitant operation of said case-shift mechanism and the "1" key, a connection may be established through which the general operator may cause a unit to be inserted in said totalizer.

58. In a combined typewriting and computing machine, in combination, a typewriting mechanism comprising number keys, a letter-spacing carriage, a platen mounted in said carriage, and case-shift mechanism for said platen, a computing mechanism comprising an algebraic totalizer, actuating mechanism therefor including digit-indexing devices and a general operator, index-setting devices controlled by said keys, the digit-indexing devices being normally out of coöperative relation with said index-setting devices, subtraction-setting mechanism 45 for varying the relation between said keys and said index-setting devices, denomination-selecting mechanism controlled in accordance with the letter-spacing movements of said carriage for establishing setting relations between said index-setting devices and said digit-indexing devices, denomination by 50 denomination, and means controlled by said case-shift mechanism for disabling said denomination-selecting mechanism, and for establishing a setting relation 55 between said index-setting devices and said digit-indexing devices, denomination by 60 denomination, and means controlled by said case-shift mechanism for disabling said denomination-selecting mechanism, and for establishing a setting relation 65 between said index-setting devices and said digit-indexing devices, denomination by 70 denomination, and means controlled by said case-shift mechanism for disabling said denomination-selecting mechanism, and for establishing a setting relation 75 between said index-setting devices and said digit-indexing devices, denomination by 80 denomination, and means controlled by said case-shift mechanism for disabling said denomination-selecting mechanism, and for establishing a setting relation 85 between said index-setting devices and said digit-indexing devices, denomination by 90 denomination, and means controlled by said case-shift mechanism for disabling said denomination-selecting mechanism, and for establishing a setting relation 95 between said index-setting devices and said digit-indexing devices, denomination by 100 denomination, and means controlled by said case-shift mechanism for disabling said denomination-selecting mechanism, and for establishing a setting relation 105 between said index-setting devices and said digit-indexing devices, denomination by 110 denomination, and means controlled by said case-shift mechanism for disabling said denomination-selecting mechanism, and for establishing a setting relation 115 between said index-setting devices and said digit-indexing devices, denomination by 120 denomination, and means controlled by said case-shift mechanism for disabling said denomination-selecting mechanism, and for establishing a setting relation 125 between the same setting device and an indexing device of said index-shifting mechanism, whereby a concomitant operation of said case-shift mechanism and the "1" key will effect a connection through 130

said index-setting devices and said digit-indexing devices of units order, so that on concomitant operation of said case-shift mechanism and the "1" key, one or the other of two connections shall be established dependent upon the setting of the subtraction-setting mechanism, through which the general operator may cause either a positive or a negative unit to be inserted in said totalizer, the character of the unit added being dependent upon which of the two connections is established. 70

59. In a combined typewriting and computing machine, in combination, a typewriting mechanism including number keys and case-shift mechanism, an algebraic totalizer, actuating mechanism for said totalizer including digit-indexing devices and a general operator, index-setting devices capable of being operated by said keys, said indexing devices being normally out of coöperative relation with said index-setting devices, denomination-selecting means for establishing setting relations between said digit-indexing devices and said index-setting devices, denomination by denomination, and means controlled by said case-shift mechanism for disabling said denomination-selecting means, and for establishing a setting relation between an index-setting device controlled by the "1" key and the "1" digit-indexing device of lowest denominational order, whereby a concomitant operation of said case-shift mechanism and the "1" key will effect a connection through which the general operator may cause a unit to be added in said totalizer. 90

60. In a combined typewriting and computing machine, in combination, a typewriting mechanism including number keys and case-shift mechanism, an algebraic totalizer including a shiftable index, actuating mechanism for said totalizer including digit-indexing devices and a general operator, shifting mechanism for said index having settable indexing devices thereon, index-setting devices capable of being operated by said keys, said indexing devices being normally out of coöperative relation with said setting devices, denomination-selecting means for establishing setting relations between said digit-indexing devices and said setting devices, denomination by denomination, and means controlled by said case-shift mechanism for disabling said denomination-selecting means, and for establishing a setting relation between an index-setting device controlled by the "1" key and one of the digit-indexing devices of lowest denominational order, and for also establishing a setting relation between the same setting device and an indexing device of said index-shifting mechanism, whereby a concomitant operation of said case-shift mechanism and the "1" key will effect a connection through 130

which the general operator will cause the totalizer index to be shifted and a unit to be added in said totalizer.

61. In a combined typewriting and computing machine, in combination, a typewriting mechanism including number keys, a platen, and case-shift mechanism for said platen, algebraic computing mechanism, means controlled by said case-shift mechanism, when the platen is in upper-case position, and the "1" number key whereby a unit may be added in said computing mechanism, and means controlled by said case-shift mechanism for disabling parts of said computing mechanism, so as to prevent control of said computing mechanism by any of said number keys except the "1" number key when said platen is in upper-case position.
62. In a combined typewriting and computing machine, in combination, a typewriting mechanism including number keys, a platen, and case-shift mechanism for said platen, algebraic computing mechanism, means controlled by said case-shift mechanism, when the platen is in upper-case position, and the "1" number key whereby a unit may be added in said computing mechanism, and means controlled by said case-shift mechanism for locking all keys, except said "1" key when said platen is in upper-case position.

63. In a combined typewriting and computing machine, in combination, typewriting mechanism including number keys, a platen, and case-shift mechanism for said platen, algebraic computing mechanism including subtraction-setting mechanism, means controlled by said case-shift mechanism, when the platen is in upper-case position, and the "1" number key whereby either a positive or a negative unit may be added in said computing mechanism, the character of said unit being determined by the setting of said subtraction-setting mechanism, and means controlled by said case-shift mechanism for disabling parts of said computing mechanism, so as to prevent control of said computing mechanism by any of said number keys except the "1" number key when said platen is in upper-case position.

64. In a combined typewriting and computing machine, in combination, typewriting mechanism including number keys, a platen, and case-shift mechanism for said platen, algebraic computing mechanism including subtraction-setting mechanism, means controlled by said case-shift mechanism, when the platen is in upper case position, and the "1" number key whereby either a positive or a negative unit may be added in said computing mechanism, the character of said unit being determined by the setting of said subtraction-setting mechanism and means controlled by said case-

shift mechanism for locking all keys except the "1" key when said platen is in upper-case position.

65. In a combined typewriting and computing machine, in combination, a typewriting mechanism including number keys, a platen, and case-shift mechanism for said platen, an algebraic computing mechanism having a shiftable index, means controlled by said case-shift mechanism, when the platen is in upper-case position, and the "1" number key whereby said index may be shifted and a unit may be added in said computing mechanism, and means controlled by said case-shift mechanism for disabling parts of said computing mechanism, so as to prevent control of said computing mechanism by any of said number keys except the "1" number key when said platen is in upper-case position.

66. In a combined typewriting and computing machine, in combination, a typewriting mechanism including number keys, a platen, and case-shift mechanism for said platen, an algebraic computing mechanism having a shiftable index, means controlled by said case-shift mechanism, when the platen is in upper-case position, and the "1" number key whereby said index may be shifted and a unit may be added in said computing mechanism and means controlled by said case-shift mechanism for locking all keys except the "1" key when said platen is in upper-case position.

67. In a combined typewriting and computing machine, in combination, a typewriting mechanism comprising number keys, a letter-spacing carriage, a platen mounted in said carriage, and case-shift mechanism for said platen, an algebraic totalizer, actuating mechanism for said totalizer including connections controlled in part by said keys, and in part by letter-spacing movements of said carriage when said platen is in lower-case position, for causing numbers typewritten to be added by said totalizer, means controlled by said case-shift mechanism for disabling said carriage-controlled key connections so as to prevent control of the actuating mechanism thereby when said platen is in upper-case position, and means controlled by said case-shift mechanism, when the platen is in upper case position, and the "1" number key whereby a unit may be added in said totalizer, irrespective of the letter-space position of said carriage.

68. In a combined typewriting and computing machine, in combination, a typewriting mechanism comprising number keys, a letter-spacing carriage, a platen mounted in said carriage, and case-shift mechanism for said platen, an algebraic totalizer, actuating mechanism for said totalizer including connections controlled in part by said keys, and in part by letter-spacing movements of said

carriage when said platen is in lower-case position, for causing numbers typewritten to be added by said totalizer, means controlled by said case-shift mechanism for disabling 5 said carriage-controlled key connections so as to prevent control thereby when said platen is in upper-case position, means controlled by said case-shift mechanism, when the platen is in upper-case position, and the 10 "1" number key, whereby a unit may be added in said totalizer, irrespective of the letter-space position of said carriage, and means controlled by said case-shift mechanism for locking all keys except the "1" key 15 when said platen is in upper-case position.

69. In a combined typewriting and computing machine, in combination, a typewriting mechanism comprising number keys, a letter-spacing carriage, a platen mounted in 20 said carriage, and case-shift mechanism for said platen, an algebraic totalizer including a shifttable index, actuating mechanism for said totalizer including connections controlled in part by said keys, and in part by 25 letter-spacing movements of said carriage when said platen is in lower-case position, for causing numbers typewritten to be added by said totalizer, means controlled by said case-shift mechanism for disabling said carriage-controlled key connections so as to prevent control thereby when said platen is in upper-case position, and means controlled by said case-shift mechanism, when the platen is in upper-case position, and the 30 "1" number key whereby either a positive or a negative unit may be added in said totalizer, irrespective of the letter-space position of said carriage, the character of said unit being determined by the setting of said subtraction-setting mechanism.

70. In a combined typewriting and computing machine, in combination, a typewriting mechanism comprising number keys, a letter-spacing carriage, a platen mounted in 40 said carriage, and case-shift mechanism for said platen, an algebraic totalizer including a shifttable index, actuating mechanism for said totalizer including connections controlled in part by said keys, and in part by 45 letter-spacing movements of said carriage when said platen is in lower-case position, for causing numbers typewritten to be added by said totalizer, means controlled by said case-shift mechanism for disabling said carriage-controlled key connections so as to prevent control thereby when said platen is 50 in upper-case position, means controlled by said case-shift mechanism, when the platen is in upper-case position, and the "1" number key whereby said index may be shifted and a unit may be added in said totalizer, irrespective of the letter-space position of said carriage, the character of said unit being determined by the setting of said subtraction-setting mechanism, and means controlled by said case-shift mechanism for locking all keys except said "1" key when said platen is in upper-case position.

65 71. In a combined typewriting and com-

puting machine, in combination, a typewriting mechanism comprising number keys, a letter-spacing carriage, a platen mounted in said carriage, and case-shift mechanism for said platen, an algebraic totalizer, actuating 70 mechanism for said totalizer including connections controlled in part by said keys and in part by letter-spacing movements of said carriage when said platen is in lower-case position, for causing numbers typewritten 75 to be added by said totalizer, said actuating mechanism also including subtraction-setting mechanism, means controlled by said case-shift mechanism for disabling said carriage-controlled key connections so as to 80 prevent control thereby when said platen is in upper-case position, and means controlled by said case-shift mechanism, when the platen is in upper-case position, and the "1" number key whereby either a positive or a 85 negative unit may be added in said totalizer, irrespective of the letter-space position of said carriage, the character of said unit being determined by the setting of said subtraction-setting mechanism.

72. In a combined typewriting and computing machine, in combination, a typewriting mechanism comprising number keys, a letter-spacing carriage, a platen mounted in 90 said carriage, and case-shift mechanism for said platen, an algebraic totalizer, actuating mechanism for said totalizer including connections controlled in part by said keys and in part by letter-spacing movements of said carriage when said platen is in lower-case 100 position, for causing numbers typewritten to be added by said totalizer, said actuating mechanism also including subtraction-setting mechanism, means controlled by said case-shift mechanism for disabling said carriage-controlled key connections so as to 105 prevent control thereby when said platen is in upper-case position, means controlled by said case-shift mechanism, when the platen is in upper-case position, and the "1" number key whereby either a positive or a negative unit may be added in said totalizer irrespective of the letter-space position of said carriage, the character of said unit being determined by the setting of said subtraction-setting mechanism, and means controlled by said case-shift mechanism for locking all keys except said "1" key when said platen is in upper-case position.

73. In a combined typewriting and computing machine, in combination, a typewriting mechanism comprising number keys, a letter-spacing carriage, a platen mounted in 110 said carriage, and case-shift mechanism for said platen, an algebraic totalizer including 115 a shifttable index, actuating mechanism for said totalizer including connections controlled in part by said keys and in part by letter-spacing movements of said carriage when said platen is in lower-case position 120

for causing numbers typewritten to be added by said totalizer, said actuating mechanism also including subtraction-setting mechanism, means controlled by said case-shift mechanism for disabling said carriage-controlled key connections so as to prevent control thereby when said platen is in upper-case position, and means controlled by said case-shift mechanism, when the platen is in upper-case position, and the "1" number key whereby said index may be shifted, and either a positive or a negative unit may be added in said totalizer irrespective of the letter-space position of said carriage, the character of the unit added being determined by the setting of said subtraction-setting mechanism.

74. In a combined typewriting and computing machine, in combination, a typewriting mechanism comprising number keys, a letter-spacing carriage, a platen mounted in said carriage, and case-shift mechanism for said platen, an algebraic totalizer including a shifttable index, actuating mechanism for said totalizer including connections controlled in part by said keys and in part by letter-spacing movements of said carriage when said platen is in lower-case position for causing numbers typewritten to be added by said totalizer, said actuating mechanism also including subtraction-setting mechanism, means controlled by said case-shift mechanism for disabling said carriage-controlled key connections, so as to prevent control thereby when said platen is in upper-case position, means controlled by said case-shift mechanism, when the platen is in upper-case position, and the "1" number key whereby said index may be shifted, and either a positive or a negative unit may be added in said totalizer, irrespective of the letter-space position of said carriage, the character of the unit added being determined by the setting of said subtraction-setting mechanism, and means controlled by said case-shift mechanism for locking all keys except said "1" key when said platen is in upper-case position.

75. The combination with the number-keys of a computing machine, of means, effective at will, for locking all except a selected one of said keys, while leaving the remaining key free for operation.

76. The combination with the number-keys of a computing machine, of a series of locking elements, means for causing said elements to lock all of said keys, and other means for causing said elements to lock all but one of said keys, while permitting the remaining key to be operated.

77. The combination with the number-keys of a computing machine, of a series of key-locking elements, means for moving and holding said elements in certain relative po-

sitions, such as to prevent the operation of any of said keys, and means for moving and holding certain of said elements in different relative positions, such as to prevent the operation of all but a selected one of said keys, which is left free to be operated.

78. The combination with the number-keys of a computing machine and a series of locking elements, mutually so related that the operation of any one of said keys will cause said elements to lock all the others, of means for so positioning certain of said elements, as to lock all but one of said keys, while permitting the remaining key to remain free for operation.

79. The combination with the number-keys of a computing machine and a series of locking elements, mutually so related that the operation of any one of said keys will cause said elements to lock all the others, of means for so positioning said elements as to lock all of said keys, and other means for differently positioning certain of said elements so as to lock all but one of said keys, while permitting the remaining key to be operated.

80. The combination with the number-keys of a computing machine, of means, effective at the will of the operative, for locking certain only of said keys, any key not so locked being free to be operated.

81. The combination with the number-keys of a computing machine, of a series of locking elements, means for causing said elements to lock all of said keys, and other means for causing said elements to lock certain only of said keys, any key not so locked being free to be operated.

82. The combination with the number-keys of a computing machine, of a series of key-locking elements, means for moving and holding said elements in certain relative positions, such as to prevent the operation of any of said keys, and means for moving and holding certain of said elements in different relative positions, such as to prevent the operation of certain only of said keys, any key not so locked being free to be operated.

83. The combination with the number-keys of a computing machine and a series of locking elements, mutually so related that the operation of any one of said keys will cause said elements to lock all of the others, of means for so positioning certain of said elements as to lock certain only of said keys, any key not so locked being free to be operated.

84. The combination with the number-keys of a computing machine and a series of locking elements, mutually so related that the operation of any one of said keys will cause said elements to lock all the others, of means for so positioning said elements as to lock all of said keys, and other means for

differently positioning certain of said elements, so as to lock certain only of said keys, any key not so locked being free to be operated.

5 85. In a combined typewriting and computing machine, in combination, a typewriting mechanism, including number-keys, a platen, and case-shift mechanism for said platen, a computing mechanism including 10 key-locking means, and means, controlled by said case-shift mechanism, for rendering said key-locking means effective to lock certain only of said keys when said platen is in upper-case position, any key not so 15 locked being free to be operated.

86. In a combined typewriting and computing machine, in combination, a typewriting mechanism, including number-keys, a platen, and case-shift mechanism for said 20 platen, a computing mechanism including key-locking means, and means, controlled by said case-shift mechanism, for rendering said key-locking means effective to lock all except a selected one of said keys when 25 said platen is in upper-case position, while leaving the remaining key free for operation.

87. In a combined typewriting and computing machine, in combination, typewriting 30 mechanism, including number-keys, a letter-spacing carriage, a platen mounted in said carriage, and case-shift mechanism for said platen, a computing mechanism including a series of locking elements, means controlled by letter-spacing movements of said carriage, for locking all of said keys, and means, controlled by said case-shift mechanism, for causing said elements to lock certain only of said keys when said platen is in 35 upper-case position, any key not so locked being free to be operated.

88. In a combined typewriting and computing machine, in combination, typewriting mechanism, including number-keys, a 40 letter-spacing carriage, a platen mounted in said carriage, and case-shift mechanism for said platen, a computing mechanism comprising a series of locking elements, means, controlled by letter-spacing movements of said carriage, for locking all of said keys, and means, controlled by said case-shift mechanism, for causing said elements to lock all except a selected one of said keys when 45 said platen is in upper-case position, while leaving the remaining key free for operation.

89. In a combined typewriting and computing machine, in combination, a typewriting mechanism, comprising number-keys, a 50 letter-spacing carriage, a platen mounted in said carriage, and case-shift mechanism for said platen, a computing mechanism including a series of key-locking elements, means, controlled by letter-spacing move-

ments of said carriage, for moving and 65 holding said elements in certain relative positions, such as to prevent the operation of any of said keys, and means, controlled by said case-shift mechanism, for moving and holding certain of said elements in different relative positions, such as to prevent the 70 operation of certain only of said keys when said platen is in upper-case position, any key not so locked being free to be operated.

90. In a combined typewriting and computing machine, in combination, a typewriting mechanism, comprising number-keys, a letter-spacing carriage, a platen mounted in said carriage, and case-shift mechanism for said platen, a computing mechanism 80 including a series of key-locking elements, means, controlled by letter-spacing movements of said carriage, for moving and holding said elements in certain relative positions, such as to prevent the operation of 85 any of said keys, and means, controlled by said case-shift mechanism, for moving and holding certain of said elements in different relative positions, such as to prevent the operation of all but a selected one 90 of said keys when said platen is in upper-case position, while leaving the selected key free to be operated.

91. In a combined typewriting and computing machine, in combination, a typewriting 95 mechanism, comprising number-keys, a letter-spacing carriage, a platen mounted in said carriage, and case-shift mechanism for said platen, a computing mechanism including a series of key-locking elements, 100 mutually so related that the operation of any one of said keys will cause said elements to lock all of the others, and means, controlled by said case-shift mechanism, for so positioning certain of said elements as to 105 lock all but one of said keys when said platen is in upper-case position, while permitting the remaining key to remain free for operation.

92. In a combined typewriting and computing machine, in combination, a typewriting 110 mechanism, comprising number-keys, a letter-spacing carriage, a platen mounted in said carriage, and case-shift mechanism for said platen, a computing mechanism including a series of key-locking elements, mutually so related that the operation of any one 115 of said keys will cause said elements to lock all of the others, and means, controlled by said case-shift mechanism, for so positioning certain of said elements as to lock certain only of said keys when said platen is in upper-case position, any key not so locked being free to be operated.

93. In a combined typewriting and computing machine, in combination, a typewriting 120 mechanism, comprising number-keys, a letter-spacing carriage, a platen mounted

- in said carriage, and case-shift mechanism for said platen, a computing mechanism including a series of key-locking elements, mutually so related that the operation of 5 any one of said keys will cause said elements to lock all of the others, means, controlled by letter-spacing movements of said carriage, for so positioning said elements as to lock all of said keys, and other means, controlled by said case-shift mechanism, for 10 differently positioning certain of said elements so as to lock certain only of said keys when said platen is in upper-case position, any key not so locked being free to be operated.
94. In a combined typewriting and computing machine, in combination, a typewriting mechanism, comprising number-keys, a letter-spacing carriage, a platen mounted in 15 said carriage, and case-shift mechanism for said platen, a computing mechanism including a series of key-locking elements, mutually so related that the operation of any one of said keys will cause said elements to lock 20 all of the others, means, controlled by the letter-spacing movements of said carriage, for so positioning said elements as to lock all of said keys, and other means, controlled by said case-shift mechanism, for differently 25 positioning certain of said elements so as to lock all but a selected one of said keys when said platen is in upper-case position, while permitting the remaining key to remain free for operation.

95. In an algebraic computing machine, 35 in combination, an algebraic totalizer having a shiftable index, actuating mechanism for said totalizer, including a set of number-keys, representative, respectively, of the digits "1" to "9," a set of index-setting devices normally representative, respectively, of the digits "1" to "9," subtraction-setting mechanism, a general operator, a normally effective operating connection from the "1" key to the "1" index-setting device, 40 when the machine is set for addition, means for shifting the connection from the "1" key to the "8" index-setting device, when the machine is set for subtraction, an operating member for said shiftable index, 45 settable means on said operating member, capable of being set by the "1" key, through the agency of the "8" index-setting device, when the machine is set for subtraction, through which the general operator may 50 impart a drive of eight steps to the index-shifting operating member, and settable means on said operating member, capable of being set by said "1" key, through the agency of the "1" index-setting device, 55 through which the general operator may impart a two-step movement to said index-shifting operating member.
